UNITED STATES PATENT OFFICE.

WILLIAM A. KING, OF MEMPHIS, TENNESSEE.

DESIGN FOR AN AUTOMOBILE-BODY.

58,766.

Specification for Design.

Patented Aug. 30, 1921.

Application filed April 12, 1920. Serial No. 373,403. Term of patent 14 years.

To all whom it may concern:

Be it known that I, WILLIAM A. KING, a citizen of the United States, residing at Memphis, in the county of Shelby and State of Tennessee, have invented a certain new, original, and ornamental Design for an Automobile-Body, of which the following is a specification.

The design is illustrated in the accompanying drawings, which are made a part hereof, wherein—

Figure 1 is a side elevation of a car embodying said design, and

Fig. 2 a sectional view taken on line 2—2 of Fig. 1 to show more clearly the inclination or taper of the longitudinal band.

The new and ornamental design for car body comprises a radiator, a hood and a body having a band 10 running the entire length of such composite members and over the back of the body as indicated at 11. This band is beveled or tapered relative to a vertical as indicated more particularly at

Fig. 2 and passes over and forms tops of the doors 12 and 13. These doors are provided with corners clipped upon angles of approximately 45° as indicated at 14. The hood is inclined along its opposite sides and is provided with ornamental ventilators 15. The particularly displayed characteristic with the design is such band 10 merging into the continuation 11 and the side doors with the lower corners clipped as indicated at 14.

I claim:

The new, original and ornamental design for an automobile body as shown and described.

In witness whereof, I have hereunto set my hand and seal at Memphis, Tennessee, this 9 day of April, A. D. nineteen hundred and twenty.

WILLIAM A. KING. [L. S.]

Witnesses:

JOHN W. FARLEY,
F. M. BAILEY.
